INSTALLATION FOR THE MEASUREMENT
AND THE CONTROL OF THE TEMPERA-
TURE IN A METAL MELTING AND PAR-
TICULARLY IN A SUBMERGED RESISTOR
TYPE INDUCTION FURNACEMario Tama, Morrisville, Pa., assignor to Ajax
Engineering Corporation, Trenton, N. J.

Application May 27, 1947, Serial No. 750,762

2 Claims. (Cl. 13—29)

1

The invention relates to the indication, measurement and control of the temperature in metal melting and particularly submerged resistor type induction furnaces. These furnaces are used at a rapidly increasing rate for the melting and casting of metal alloys and for similar operations which necessitate a very exact temperature control.

The induction furnaces answer this requirement satisfactorily because their operating conditions can be easily adjusted to the desired processing temperatures with a high degree of accuracy.

In order to maintain the temperature of the molten metals within a predetermined narrowly limited range the continuous uninterrupted measuring and control of the temperature is an important requisite.

Submerged resistor type indicator furnaces are, as commonly known, composed of a hearth and a secondary melting loop which are housed in a refractory lined metal casing.

The melting loop consists in modern induction furnaces as for instance disclosed in prior U. S. Patents No. 2,339,964 of Manuel Tama, No. 2,342,617 of Manuel Tama and Mario Tama, Re-issue Patent No. 22,602 of Mario Tama, No. 2,381,523 of Manuel Tama and Mario Tama and No. 2,375,049 of Manuel Tama and Mario Tama, of a channel, which is spaced from the hearth, for instance, a bottom channel and of channel sections connecting this spaced channel and the hearth; the melting loop is at its outlet or outlets through the furnace wall closed by a removable refractory plug.

The metals to be molten and to be processed, for instance, cast from the furnaces are charged in the solid state through an upper opening into the hearth.

The hitherto customary temperature measuring method consists in immersing the measuring instrument, for instance, a thermocouple having a protecting tube through the upper charging opening into the hearth.

This practice is objectionable. The instrument is directly exposed to the contact with the charged materials and therefore, subject to injury and breakage. The result is that today the maintenance expenses for thermocouples are many times higher than the costs for maintaining the refractory lining of the entire furnace in proper working condition.

In aluminum alloy foundries cast iron tubes are used for the protection of the thermocouples. This measure does not prove a remedy because

2

the iron is quickly dissolved and contaminates the molten metals.

The protective tubes are coated with refractory washes to prevent contamination of the molten charge, but the renewal of the coatings which has to be effected at least every 24 hours is a source of continuous trouble and expense.

The substitution of iron tubes by refractory materials, for instance, by silicon carbide tubes has its merits. Silicon carbide is a good heat conductor and responds to slight temperature changes, silicon carbide is not attacked by the molten metals, for instance, molten aluminum, but is, however, easily breakable.

In order to avoid these various disadvantages and to protect the thermocouple tubes against breakage and wear it has been suggested to introduce the measuring instrument into downwardly inclined passages provided in the furnace wall in such a manner that the protective tube does not extend into the hearth proper but ends within the passage short of the inside face of the furnace wall. The inner surface of the furnace wall is provided with a protrusion or bulge tapering into the walls of the furnace having a recess therein at the point where the passage opens into the hearth.

Consequently the instrument will only measure the temperature of the very small fraction of the stagnant molten charge which ascends into the inclined passage. The temperature thus measured by the instrument is different from the temperature of the bulk of the charge.

It is the primary object of this invention to provide temperature measuring and controlling means for use in metal melting and particularly in submerged resistor type induction furnaces which permit a continuous, exact and reliable indication of the true operating temperature of the furnace or the bath respectively.

It is also an important object of the invention to so locate the measuring instrument, such as a thermocouple, in the furnace that it is not contacted by the fresh charge and therefore protected against its damaging action.

It is a further object of the invention to place the thermocouple within the furnace in direct contact with that main portion of the charge which is continuously moved and circulated through the furnace and therefore has the true average operating temperature.

It is a further object of the invention to avoid repair and renewal of the thermocouple and to eliminate the hitherto customary unusually high costs of temperature indication in metal melting

and particularly in submerged resistor type induction furnaces.

With these and additional objects in view which will become apparent as this specification proceeds, this invention comprises in its broad aspect the placement of the measuring instrument and particularly a thermocouple provided with a refractory protection tube in a section of the metal melting furnace which is spaced from the metal charging opening and the hearth and is interposed in the flow movement of the molten metal from the charge opening and/or the hearth; accordingly the instrument is protected against damage by the fresh charge but still kept in contact with that main portion of the metal bath which has the true temperature to be measured. In its application to a submerged resistor type induction furnace the thermocouple tube is placed in a closing plug of the furnace in such a manner that it projects into the metal conducted through the loop; a recess is preferably provided in the plug adjoining furnace wall to protect the projecting tube end against damage.

The invention is particularly well applicable to induction furnaces of the above mentioned type, where the melting loop is composed of a channel spaced from the hearth which, for instance, may be a bottom channel and channel portions connecting the channel with the hearth.

If used in connection with these furnaces the thermocouple tube projects into a lateral extension of the bottom channel; the plug as well as the plug accommodating furnace wall is recessed so that the projecting tube end is protected against the cleaning tools which are introduced from above into the melting loop. However, the invention is equally well applicable to any other type of metal melting or induction furnaces as long as the metal bath is kept in movement.

Several modes of mounting the thermocouple in submerged resistor type induction furnaces are shown in the accompanying drawings.

In the drawings,

Fig. 1 is a vertical sectional elevation of an induction furnace disclosed in the above mentioned patents and having the thermocouple installed in conformity with this invention,

Fig. 2 is a sectional view on line 2-2 of Fig. 1,

Fig. 3 is a vertical sectional view showing the application of the invention to an induction furnace provided with an arcuated melting loop.

The furnace shown in Fig. 1 comprises a hearth 1 and a secondary melting loop located underneath the hearth and composed of channel 2, two lateral channels 3 and a center channel 4, the lateral and the center channel connecting channel 2 and hearth 1.

The furnace is housed in a casing 5 provided with a refractory lining 6.

The secondary blocks 7 accommodate the primary and the secondary loop, the primary being composed of an iron core 20 and a coil 21 which is insulated by an asbestos sleeve 22.

Channel 2 is provided with plugs 11, 12. Insofar the furnace is similarly built to the furnaces which are disclosed in the above mentioned patents of applicants.

In conformity with this invention the bottom plug 11 is provided with a bore and this bore accommodates the thermocouple tube 13 which consists of a suitable refractory material, such as for instance siliconcarbide or graphite; the tube is sealed in the plug bore by a refractory cement layer 14; the inside of the tube which

5 accommodates the measuring element 15 may be filled with clay particles 16 to hold the element in proper place. In this manner the instrument is located in a section of the furnace which is spaced and separated from the charging opening and from the hearth but is in direct contact with that portion of the metal which is constantly moved from the hearth through the loop and therefore has exactly that temperature which must be measured. Moreover, the instrument tube 13 protrudes outside of plug 11 which further enhances the correctness of the measurement.

15 A space 18 is recessed from the refractory furnace wall which space in this case forms an extension of the bottom channel 2. As the length of this recess is substantially equal or slightly smaller than the lengths of the projecting tube end, the instrument is protected against the 20 cleaning tools which are inserted from above into the channels 3.

The location of the thermocouple 13 in Fig. 3 is the same as in Fig. 1; the only difference is that the thermocouple is here associated with the arcuated melting loop 15.

In order to fully apprehend the significance of this invention a short explanation of the manner of measuring the temperature in metal melting induction furnaces will be helpful.

The readings of the thermocouple are connected to a temperature controller, which in turn regulates the operation of the contactors leading the power to the furnace. There are two methods of control.

One is called the on-off control and the other the high-low control.

In the on-off control only one contactor is used which connects full power of the furnace as soon as a minimum temperature is reached and disconnects the furnace entirely when the maximum temperature is reached.

In the high-low control, two contactors are used, one for full power and the other for low power. The low powered tap does not provide enough power to hold the temperature of the furnace, while the high powered tap is sufficient to raise the temperature rapidly. When maximum temperature is reached, the high power contactor is disconnected and the low power contactor is connected. When minimum temperature is reached, the operation is reversed; the high tap goes on and the low tap goes off.

With both of these temperature controls it is necessary that the control instrument is located at the proper place. If the thermocouple extends into the bath located in the hearth, as hitherto customary, it will come in contact with the cold metal charged into the furnace and show a temperature which is too low.

60 However, if it is placed to extend into the melting loop or a melting channel in conformity with this invention, it will show the correct average temperature, because due to the energetic circulation easily obtainable in these furnaces, the thermocouple will measure the desired true bath temperature and still be fully protected against breakage and other injuries.

This great advantage is particularly apparent in furnaces where a unidirectional flow of the molten metal is obtained, as for instance disclosed in U. S. application Serial No. 735,851.

Whereas the temperature in the section of the hearth into which the solid metal is charged greatly differs from the true temperature of the bath, the temperature of the metal into which

the thermocouple projects according to this invention is the actual operating temperature of the furnace or of the bath because it is the temperature of the metal which is in constant movement and circulation through the melting loop and the major portion of the hearth.

Temperature measurements carried-out in a 60 kw. twin-coil furnace of the type disclosed in U. S. Reissue Patent No. 22,602, prove the measuring accuracy and reliability of this invention.

When the furnace was operated with the full power of 60 kw. the temperature difference of the metal in the hearth and in the melting loop was between 40 to 50° F., when operated with 20 kw. the difference was only between 10 to 20° F. The same furnace equipped with the unidirectional flow means according to U. S. application Serial No. 735,851 only shows a difference of 10° F., which is well within the range of error of customary thermocouples.

From the above it is apparent that the invention is particularly well applicable to induction furnaces provided with a thorough circulation of the molten charge and that in this manner for the first time an automatic temperature control has been achieved in induction furnaces.

The very small temperature differences in induction furnaces which are equipped to produce a thorough metal circulation demonstrate that the location of the thermocouple in conformity with this invention satisfactorily corresponds to the requirements of a reliable temperature measurement, whereas its application in prior art furnaces having considerable temperature differences in the hearth and in the melting channels is of minor avail.

By the placement of the thermocouple in the loop closing plug and the recessing of a space into which the tube end projects, the instrument is adequately protected against breakage and contact with the cleaning tools which are introduced from above into the furnace.

If the instrument must be repaired or the tube must be replaced which may happen after an extended period of use, this is without any difficulty or injury to the furnace wall effected by the easy removal of the plug and the location thereon of another thermocouple.

The invention, therefore, assures a continuous automatic temperature measurement and control in metal melting furnaces and eliminates at the same time breakage or injury of the measuring

instrument; moreover, reliable measurements are obtained of the true operating temperature of the furnace and of the molten charge.

What I claim is:

1. In a submerged resistor type induction furnace a hearth, a secondary melting loop composed of a bottom channel and channels connecting the bottom channel with the hearth, a primary transformer assembly threading said secondary loop adapted to hold metal in the molten state and to cause its circulation through the hearth and the melting loop, a refractory lined casing housing the furnace, an outlet extending from the bottom channel through the lower portion of the casing, a plug ending short of the furnace lining to close said outlet whereby a recess directly connected with the melting loop is formed which is protected against mechanical attack by cleaning tools and a thermocouple located in said plug projecting with the end of its measuring tube into said recess.
2. In a submerged resistor type induction furnace for melting metals a hearth to hold a molten metal bath, a secondary melting loop to circulate the molten metal through said hearth, a primary transformer assembly threading said melting loop, a refractory casing enclosing said hearth, said melting loop and said transformer assembly, an outlet extending from said melting loop through the lower portion of the casing, a plug to close said outlet and a thermocouple having a protective refractory tube being inserted into said plug and reaching with its protected measuring end into said melting loop.
